(57) **CLAIM**

The ornamental design of a race car, as shown and described.

DESCRIPTION

FIG. 1 is a perspective view of a race car showing our new design;

FIG. 2 is a side elevational view thereof;

FIG. 3 is an opposite side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of a race car showing second embodiment of our new design;

FIG. 9 is a side elevational view of FIG. 8;

FIG. 10 is an opposite side elevational view of FIG. 8;

FIG. 11 is a top plan view of FIG. 8;

FIG. 12 is a bottom plan view of FIG. 8;

FIG. 13 is a front elevational view of FIG. 8; and,

FIG. 14 is a rear elevational view of FIG. 8.

The wheels shown in broken lines throughout the drawing specification are shown for illustrative purposes only and form no part of the claimed design.
